United States Patent Office.

ROBERT LEAMAN, OF HILLSBOROUGH, OHIO.

Letters Patent No. 60,911, dated January 1, 1867.

IMPROVEMENT IN LOUNGES FOR INVALIDS.

The Schedule referred to in these Letters Patent and making part of the same.

TO ALL WHOM IT MAY CONCERN:

Be it known that I, ROBERT LEAMAN, of Hillsborough, Highland county, in the State of Ohio, have invented certain new and useful improvements in Lounges; and I hereby declare that the following is a true, full, and exact description of the same, reference being had to the accompanying drawings, and to the letters of reference marked thereon.

In the annexed drawings, which are made, a part of this specification—
Figure 1 represents a side elevation of my lounge.

Figure 2 is a plan view of the same, with the lounge folded back to a vertical position.

The frame R, in which the lounge is placed, consists of the uprights A, strengthened by the braces B and cap-piece O, the lower ends of said braces resting on sills, C; these sills being held firmly together at their end by the ties e. In order to give the lounge its proper elevation when placed in position, the support s is provided, and consists of a lateral bar, sustained at each end by a leg, n. E represents the lounge frame, consisting of the side rails g, bound together at their lower ends by the foot-board h, and near the head of the lounge by the cross-tie d. Outside of tie d, and parallel with it, is shaft k, with the pulley m on it, the pulley being placed midway between the two side rails g. The side rails rest near their lower end on the bar L, the ends of which are rounded, and act as pivots, which play in holes made through the braces B. By means of this bar the lounge can be raised or lowered, as hereinafter described. It will be observed that the side rails g are jointed in two places; one set of joints being near the middle of the rails, and the other set near the foot-board h. These joints are made by a vertical mortise cut through the end of one section of the rail g to receive the tenon formed on the adjoining section; the said tenon being rounded at outer end so as to allow the mortised section to play with a vertical motion. Underneath the lounge frame is placed the shaft H, which works in holes cut through cleats P; the cleats being screwed to the bottom of the sections of the rails, which are furnished with tenons, and extending the necessary distance along the bottom of the mortised section, and there kept in position by the buttons i. The shaft H extends at one end sufficiently far beyond the rail to admit of the ratchet-wheel T being placed on it, and also the crank b, for operating shaft H. Near the top of uprights A is pivoted the shaft N, which has on it the pulley V; the pulley being midway between the uprights. In operating my lounge, which is intended chiefly for feeble and aged persons, one end of a cord, a, is fastened to tie d, passed over pulleys V and m, and then secured to shaft H. If the occupant of the lounge desires to assume a perpendicular position, he will turn the crank from right to left. The cord will then wind around shaft H until the lounge is brought to vertical position between the uprights A, and the occupant in a situation to step off the lounge. Should he wish to raise his body erect while his legs remain in a horizontal position, he will turn the buttons i to one side, so as to remove them from the ends of the cleats P; he will then operate the crank and raise the jointed ends of the rails upon which his body rests, while the remaining sections of the rails continue stationary. To prevent the ratchet T from turning back, the pawl t is provided and hinged to the side of cleat P. In order to make a seat at the lower end of the lounge, remove the buttons i to one side, and turn the jointed section near the foot-board downward at right angles with the remaining sections of the rails g, and the object is accomplished.

Having thus described my invention, what I claim, and desire to secure by Letters Patent, is—

1. I claim the jointed rails g g, in combination with cleats P P and buttons i i, the whole arranged and operating as and for the purpose herein set forth.

2. The employment of pulleys m and V, cord a, and frame R, when used in combination with jointed rails g g, the whole constructed and operating in the manner and for the purpose herein specified.

In testimony that I claim the foregoing, I hereunto affix my signature in the presence of two witnesses:

Witnesses:
